PNEUMATIC CLEANER

Daniel Benson Reogle, Berkeley, Calif., assignor to The Ohio Citizens Trust Company, Toledo, Ohio, a corporation of Ohio, as trustee

Application January 30, 1937, Serial No. 123,286

29 Claims. (Cl. 15—16)

The invention relates to pneumatic cleaners, and more particularly to manually portable suction cleaners comprising (1) a wheeled body portion which generally includes the suction producing fan having an exhaust outlet, (2) a handle movable with reference to the body portion and (3) a dust collector bag supported by the handle. In cleaners of this type as heretofore employed, the neck of the dust collector bag has generally been secured directly to the exhaust outlet of the fan, and accordingly when the handle is moved upwardly and downwardly, in ordinary cleaning operation, flexing of the bag particularly at the neck thereof, necessarily results. For this reason dust collectors composed of paper alone have generally been found inadequate, since there is danger of the paper splitting or breaking at the point where the strain is exerted, and accordingly more expensive bags composed of fine mesh cloth have been employed with cleaners of the swinging handle type. Where cloth bags are employed as the filtering means, such bags are generally too expensive to be thrown away when filled with dust, and accordingly it is necessary to empty the dust from such bags, which is an unsanitary proceeding.

The use of porous paper dust collecting bags with pneumatic suction cleaners has been proposed, but prior to the present invention the only successful use of such bags has been in conjunction with cleaners of a type in which the cleaner handle is rigid with the body of the cleaner whereby strain on the mouth of the bag is avoided, such a cleaner being illustrated in my Patents No. 1,345,550 dated July 6, 1920, and No. 1,416,876 dated May 23, 1922.

As stated above, an ordinary porous paper dust collector bag which is sufficiently cheap to be thrown away, cannot be successfully employed with a cleaner of the swinging handle type unless special precautions are taken to prevent strain particularly on the mouth portion of the bag, since if the mouth of the ordinary unreinforced paper bag is connected directly to the rigid exhaust outlet of the cleaner the bag will soon be ruptured by the strain to which it is subjected by the repeated movement of the handle, resulting in spilling of the contents of the bag.

The danger of rupturing the bag may be lessened by suitably reinforcing the paper of which it is composed externally or internally or on both surfaces by means of a netting or cover of relatively coarse mesh material which permits the air to pass freely therethrough, while at the same

time suitably supporting the porous paper when the dust collector bag is inflated.

According to my invention the mouth of the bag is placed in communication with the rigid fan exhaust outlet of the cleaner by means of a strong flexible neck, tube or connector which is of sufficient flexibility to minimize the strain on the mouth of the bag when the handle is flexed. Means are also provided for supporting the mouth of the bag from the handle whereby the movement of the handle is absorbed by the flexible tube without strain on the bag. The flexible connector may be either in the form of a separate tube, which may be of rubber or rubberized material of sufficient length and flexibility, or the neck of the bag may be sufficiently reinforced as by means of netting adhesively secured to the surface of the paper, to permit the neck to be secured directly to the fan discharge outlet.

Even an unreinforced paper bag, which may be very cheaply manufactured, may be employed with a cleaner of the swinging handle type where special precautions are taken to confine the locus of flexibility wholly to the flexible connector, thus eliminating strain on the bag mouth. In such cases however it may sometimes be found desirable to provide an outer reinforcing covering which may be removable from the inner bag, such as is set forth for example in my Patent No. 1,416,876 dated May 23, 1922, since the outer covering may serve as a protection against rupturing of the bag proper by contact with outside objects, such as furniture and the like.

The present application is a continuation-in-part of my application Serial No. 499,575 filed December 2, 1930 and of my application Serial No. 552,050 filed July 20, 1931.

The principal object of the present invention is accordingly to provide means whereby a relatively inexpensive porous paper dust collecting bag may be employed with a cleaner of the swinging handle type.

Another object is to provide suitable reinforcement for the surface of such a bag.

A further object is to provide the bag with a suitable neck or flexible conduit or connector which communicates with the fan discharge outlet and which is of sufficient length, strength and flexibility to absorb the strains without rupturing.

Another object of the invention is to provide suitable means for supporting the bag, particularly adjacent the mouth thereof, so that the locus of flexibility will be confined to the flexible neck or connector.

50

55

Other objects will be apparent from the further detailed description.

The invention will be more readily understood by reference to the accompanying drawings and the further detailed description in which are set forth for the purpose of illustration certain specific embodiments which are intended as illustrative only but not as in any way limiting the invention to the precise details set forth.

5 10 In the drawings:—

Fig. 1 is a side elevation of a cleaner and bag embodying my invention.

Fig. 2 is a detailed section on line 2—2 of Fig. 1 showing the means for supporting the bag neck.

15 Fig. 3 is a detail view showing one of the flexible conduits or connectors used in this embodiment of my device.

Fig. 4 is a fragmentary view showing a portion 20 of a modified form of bag adapted for use with the cleaner shown in Fig. 1 as well as with the other forms of the cleaner herein disclosed.

Fig. 5 is a side elevation of a cleaner and bag showing another embodiment of my invention.

25 Fig. 6 is a section on line 6—6 of Fig. 5 showing the support for the bag neck.

Fig. 7 is a side elevation showing a cleaner of the type shown in Fig. 1 equipped with a bag mounted in a wire cage.

30 Fig. 8 is a section on line 8—8 of Fig. 7 showing the support for the neck of the bag.

Fig. 9 is a side elevation showing the invention applied to a conventional form of cleaner and employing a different form of bag provided 35 with an integral reinforced neck.

Fig. 9a is a detail view of the bag supporting member.

40 Fig. 10 is a side elevation of a cleaner similar to that shown in Fig. 9 but equipped with a reinforced bag and a separate flexible connector or neck.

45 Fig. 11 is a side elevation showing a further modification wherein the cleaner is equipped with a guard frame which supports the bag and bag neck and a portion of which serves as a housing for the conduit supplying current to the fan motor.

Fig. 11a and 11b are details showing the bag supporting member.

50 Fig. 12 is a further modification wherein a cleaner of the type shown in Fig. 1 is provided with a bag externally reinforced by fabric netting throughout its extent and supported from the cleaner handle at its rear end and adjacent 55 the neck of the bag.

Fig. 13 is a detailed section showing material from which a bag may be manufactured and composed of porous paper reinforced with netting on both sides thereof.

60 Fig. 14 is a similar view wherein the paper is reinforced on one side only.

Fig. 15 is a fragmentary plan view showing a netting reinforced surface.

Fig. 16 is a similar view wherein a different 65 form of reinforcement is employed.

The cleaners herein described are of the portable type and each includes generally a wheeled body portion comprising a floor tool, and a motor driven fan having a discharge outlet. The body

70 member is adapted to be moved to and fro across the floor, and for this purpose is equipped with a handle swingingly connected with the body which handle serves as means for moving the cleaner. A dust collector element is suspended beneath the handle and may be composed wholly

75 or in part of porous paper, which is cheap enough so that it may be thrown away when filled with dust. A flexible hollow conduit or connector either integral or separate from the bag mouth extends between the bag and the fan discharge outlet.

In the construction shown in Fig. 1 reference numeral 10 denotes a casing housing a motor (not shown) which drives a fan 12 mounted within a fan casing 11 and having a discharge outlet 10 13. A rotatable valve cap 14 such as is disclosed in my Reissue Patent No. 16,224 is provided at the inlet to the fan chamber and is adapted to connect the fan chamber with a passage 15 leading to a floor tool 16, or by reversing the valve 15 to connect the fan chamber to a passage 115 communicating with a hollow suction handle through a flexible tube 17. One such tube is shown in detail in Fig. 3 although it will be understood that various forms of flexible tubes may be employed. 20 In the form shown the tube is of the armored type being composed of relatively stiff sections flexibly connected one to the other so that the tube is of very substantial construction while at the same time readily yielding to up and down 25 movement of the handle. The tube is adapted to be removed when desired and may be replaced with another flexible tube, of any suitable character.

25 The removable handle represented by the reference numeral 18 is of the suction type and preferably composed of hard fiber, bakelite or other non-conducting material as disclosed in my Patent No. 1,292,963, dated January 28, 1919, altho' a metal pipe may be employed if desired. 30 A lead wire 19 supplying current to the fan motor runs along the side of the suction handle 18 and where the handle is of non-conducting material it will be evident that no danger of short circuiting will be involved.

35 The handle 18 is hingedly mounted with reference to the body member. As shown a collar 20 is provided adjacent the fan outlet 13, said collar being provided with a pair of branching bracket arms 21, one only being visible in the side elevation. To the outer ends of said arms are hingedly connected another pair of bracket arms 23 projecting from a collar 24 into one end of which the hollow handle 18 fits while the flexible tube 17 fits into the other end. 40 Both the handle 18 and tube 17 are removable from the collar 24.

45 A cleaner bag 25 is composed principally of porous paper which may be reinforced as by means of fabric netting composed of widely spaced strands 26 to give added strength. In Fig. 1 the netting is shown as internal and in Fig. 12 the netting is external. The bag may be cheaply constructed by gluing the strands to the paper during the course of manufacture 50 of the bag, or the bag may be equipped with a more expensive removable cover. Where permanently attached strands are employed the entire bag is sufficiently cheap so that it may be thrown away when filled with dirt but when 55 a separable cover is employed only the inner bag will be thrown away. A suitable clasp 126 may be provided at the end of the bag remote from the mouth thereof, the same being suspended from the handle 18 adjacent its rear 60 and upper end.

65 As shown a flexible tube 28 communicates with the interior of the bag preferably through the medium of a separate thimble connector or deflector 29 which may be similar to the 70

deflector shown in my prior Patent No. 1,416,876 dated May 23, 1922. This deflector is preferably rigid and accordingly lends rigidity to the mouth of the bag serving to hold the same open. 5 As shown the mouth and neck of the bag, the thimble or deflector and the end of the flexible tube 28 are all supported by a link or loop 30 suspended from a hook 31 at the lower portion of the handle. The link 30 supports the weight 10 of the connector.

This link or loop may be simply a metal ring or may be of flexible or elastic material having sufficient strength to support the weight of the connector members and confines the locus of 15 flexibility to the relatively strong flexible tube 28 thereby avoiding strain on the bag adjacent its mouth. This tube may be of armored construction similar to the tube 17 or may be of rubber or rubberized material, as illustrated in 20 Fig. 4, so that all the filtering takes place within the bag itself rather than in the connection. However the flexible connector where suitably reinforced, may be integral with the bag itself and may have some porosity, as illustrated in 25 Figs. 9 and 12. It will be noted that the axis of the hinge 32 connecting the brackets 21 and 23 passes centrally through the hollow tube 28 intermediate its ends so that the handle and bag both swing about the same pivot point, this 30 being an additional factor in reducing the strain on the bag mouth. This feature is claimed in my prior application Serial No. 499,575 filed December 2, 1930.

In Fig. 4 there is shown a modified form of 35 bag and flexible tube which are adapted to be used with the assembly shown in Fig. 1 or in other forms of cleaners herein illustrated. The bag 25a is shown as composed of unreinforced porous paper into the mouth of which bag there 40 is inserted a flexible tube 28a one end of which fits into the mouth of the bag and serves as a deflector 29a while the other end is adapted to be connected to the fan discharge outlet. The connector and bag mouth are adapted to be 45 supported by link 30a from the handle just as in the previously described embodiment of the invention so that strain on the bag is relieved. The tube 28a together with the deflector on the end thereof may be composed of non-porous 50 flexible material such as rubber or rubberized fabric. It will also be understood that this form of bag and connector may be used in assemblies other than those herein illustrated. The bag 55 itself may be reinforced in any suitable manner, either externally or internally or both, the reinforcement being either permanently secured to the surface of the paper or removable therefrom.

In Figs. 5 and 6 there is shown a modified 60 form of cleaner of the general type disclosed in my Patent No. 2,009,455 dated July 30, 1935 wherein certain details of construction are specifically claimed. The body of the cleaner is substantially the same as that illustrated in Fig. 65 1 as is also the suction handle 18 which accordingly need not be described again in detail. The connecting tube 17a in this form of apparatus is preferably permanently secured in place as distinguished from the construction described in 70 connection with Fig. 1 wherein the connector 17 is removable. In the present form of apparatus the brackets 21a and 23a are hinged at 32a, the axis of such hinge passing through 75 the center of the tube 17a. Flexibility between the bag 25 and the fan outlet 13 is provided

by means of an elbow connection 28b which insures a fluid tight joint while at the same time permitting free movement of the handle and the cleaner bag attached thereto. This connection is more specifically described in my 5 Patent No. 2,009,455. The link 30a is similar to the link 30 of Fig. 1 and may be composed either of flexible material such as rubber or may be a metal ring. In any event the locus of flexibility is substantially confined to the elbow joint 28b. 10 The dust collector bag 25b is preferably composed of porous paper and may be provided with an outer reinforcing cover 26b of cloth or other suitable fabric having a mesh relatively large as compared with the mesh of the porous paper 15 as set forth in my Patent No. 1,416,876. The inner bag may be removed from the outer cover and as shown the outer cover is provided with an extended opening along the bottom and preferably including the front end, which opening 20 may be provided with a zipper closure 39 thus permitting the paper bag to be removed when fouled and replaced by another bag. It will be obvious that other means of opening and closing the outer bag may be employed such as is 25 illustrated in my Patent No. 2,016,285 for example. It will be also apparent that this form of composite bag may be used with the other modified forms of the cleaner herein illustrated as for example with the form of cleaner shown in 30 Fig. 1, or with other forms of cleaner.

In Figs. 7 and 8 there is shown a cleaner body and handle similar to what is illustrated in Fig. 1, and accordingly these parts need not be again described in detail. In this cleaner however the 35 paper bag 25 is shown as externally reinforced by means of a wire netting or cage 40 which, as shown, is hinged at the bottom at 41 and is adapted to clasp the bag between the two halves of the cage. Clasp members 42 of any suitable construction, may be employed for releasably securing the assembled bag and support to the handle of the cleaner. At the front of the cage 40 there is provided a yoke or bracket member 43 which clasps the neck of the bag when the 45 two halves of the cage are clamped together as best illustrated in Fig. 8 at the junction between the flexible connector 28c and the deflector 29c. This yoke member accordingly serves as a substantially rigid support for the bag mouth and 50 neck and for the mating ends of the flexible connector 28c and deflector 29c and as shown extends downwardly from the handle to which it is rigidly clamped. The remainder of the cage 55 serves to reinforce and support the paper bag while permitting air to flow freely therethrough. The flexible connector 28c may be composed of rubber, rubberized material or may be of the armored type or if desired a swingingly flexible connector similar to what is shown in Fig. 5 may 60 be employed with a bag enclosed in a wire cage.

It will be noted that the cage includes a number of longitudinal wires 44c substantially co-extensive with the length of the bag, connected at their front ends to the wires which form the 65 yoke or bracket 43 and which serve as stiffening means for the inner bag. In this manner the locus of flexibility is substantially confined to the flexible connector or neck 28c thereby relieving the bag of strain. If desired the paper bag may 70 be further strengthened by mosquito netting or other fabric of relatively coarse mesh contacting externally and/or internally with the paper, which netting may be in the form of an outer bag either secured to or removable from the paper, 75

as already described in connection with other embodiments of the invention.

In the various forms of device heretofore described cleaners of the suction handle type as represented by my Patent No. 1,292,963 dated January 28, 1919 have been disclosed. The invention in its broadest aspects however is not confined to use with this type of cleaner. Thus in Fig. 9 the invention is shown applied to a swinging handle cleaner of conventional type including a floor tool 16d, a fan motor 10d located at the top of the body and above the fan casing instead of underneath as in the form previously described, the fan casing having a fan discharge outlet 13d. The handle 18d may be of any suitable type and as shown detachably fits into a collar 24d having forked bracket arms 23d (one only being shown) pivoted to the body of the cleaner as at 32d.

20 The dust collecting and air filtering bag 25d is composed of porous paper and the neck 28d of the bag is shown as externally reinforced with netting which may be adhesively and permanently secured thereto. The neck or flexible conduit 28d as shown is integral with the remainder of the bag and may be rubberized if desired to prevent passage of air therethrough or may be left porous. Sufficient reinforcement may be provided by the integral netting to permit the neck to be 30 directly secured to the outlet pipe 13d without any intermediate separable connection.

To avoid strain on the unreinforced portion of the bag particularly adjacent the neck thereof a rigid member 43a extending downwardly from the handle 18d and attached thereto supports the upper end of the bag neck adjacent the bag itself and confines the flexure to the reinforced portion 28d which is sufficiently strong so that it does not rupture even under repeated flexing. 40 The function of this member 43a is thus generally similar to that of the yoke or clasping member 43 described in connection with the embodiment shown in connection with Figs. 7 and 8. The rigid member 43a supporting the bag mouth from the handle may be extended downwardly along one 45 end of the bag and a brace member 44 attached at its upper end to the handle may be employed to give the same additional rigidity.

The rear end of the bag is shown as provided 50 with a clasp member 126d which may be detachably secured to the handle 18d. It will also be understood that the brace member 44 is detachable from the handle, and having been so detached the other bag supporting members may 55 be removed from the handle leaving it free for the attachment of any other type of bag. Ordinarily the bag will be removed by simply detaching the neck 28d from the fan outlet 13d and then withdrawing the bag rearwardly so that its 60 neck slides out of the loop in the attaching member 43a.

A similar rigid neck support may be employed if desired for the other forms of bags herein disclosed; thus in Fig. 1 a rigid bracket may be 65 substituted for the swinging link or loop 38. Instead of the integral reinforced neck 28d shown in Fig. 9 one may employ a separable flexible connector such as has been described in the other forms of the device. One may also employ 70 a reinforcement for the entire surface of the bag and not only for the neck portion. Such reinforcement may be either in the form of an integral netting or may be a removable cloth cover or a wire cage as disclosed in the previously 75 described embodiments of the invention.

One such modification is shown in Fig. 10 wherein a cleaner like that illustrated in Fig. 9 is shown provided with a bag 125d reinforced externally by suitable netting which may be adhesively secured to the paper or may be in the form of a removable cloth or wire cover. The flexible connector or neck 128d is shown as detachably connected at one end to fan outlet 13d and at its other end to a stiff collar or insert 29d similar to what is disclosed in my Patent No. 1,416,876, which insert serves to hold the bag mouth open. The bag mouth portion and the meeting ends of the flexible connector 128d and collar 29d are supported within the loop of the rigid supporting member 43a so that the locus of flexibility is confined to the neck 128d which may be of rubber, or other suitable material, preferably non-porous.

In Fig. 11 there is shown a cleaner having a body portion similar to what is shown in Fig. 1 except that the motor 10e extends directly rearwardly instead of downwardly and rearwardly from the fan casing 11e. A body such as is shown in my prior Patent No. 1,292,963 dated January 28, 1919 may be suitably employed. In this construction a loop 43b which forms part of a U-shaped bag supporting member 50 attached to the handle rigidly supports the bag mouth as well as the mating ends of the deflector 29e and the flexible hose 28e. This U-shaped frame 30 is connected to the handle 18e which handle detachably fits into the collar 24e. In this form of device not only is the neck of the bag rigidly supported as in the embodiments shown in Figs. 9 and 10 but the U-shaped member 50 extends 35 the entire length of the bag and serves as a guard frame therefor, the bag being detachably connected at three corners by clasps 51 while the fourth corner is detachably supported within the loop 43b. A portion of the guard frame and bag 40 supporting member may be made hollow so as to constitute a housing for the electrical conductor 19e which supplies current to the fan motor 10e. In this form of device the flexible members 11e and 28e are preferably removable and 45 replaceable, this being also true of the handle 18e which may be withdrawn from the bag supporting member by simply rotating the handle to unscrew it from the collar 24e after which it 50 may be withdrawn rearwardly.

The cleaner is provided with a suitable nozzle or floor tool 16e of any desired form, and a rotatable valve 14e, similar in function and in operation to the valve 14 described in connection with Fig. 1, may be employed for selectively placing the floor tool 16e or the suction handle 18e in communication with the fan 12e, as more fully described in my Reissue Patent No. 16,224. 55

The U-shaped frame 50 is connected to the body of the cleaner by means of hinged brackets 60 21e and 23e, their pivotal axis 32e passing through the flexible connector 28e, one end of which communicates with the fan outlet 13b while the other end is connected to a collar or deflector 29e 65 which enters the bag mouth, as described in connection with Fig. 1. The bracket arms 21e extend from a collar 20e surrounding the fan outlet, while the bracket arms 23e are shown extending from the collar forming the loop or eye 43b into which snugly fit the mouth of the bag 70 and the meeting ends of the flexible connector and of the collar or deflector 29e.

These members are thus rigidly supported by that portion of the frame 50 which extends downwardly from the handle, while the three clips 51 75

connect the bag to the frame at the other three corners. The rigid portion of the handle 18 is flexibly connected to the body portion through the hollow connector 17e in a manner similar to that described in connection with Fig. 1. The embodiment shown in Fig. 11 is disclosed in my application Serial No. 499,575 in which application certain details of construction are specifically claimed.

10 The bag 25e may be of porous paper reinforced or not as desired or may be provided with a separable outer cloth cover such as is shown in my Patent No. 1,416,876 for example. The bag might be provided with an integral reinforced neck such as is shown in the embodiment set forth in Fig. 9, such neck being connected to the fan outlet without the use of an additional flexible hose.

In the modification shown in Fig. 12 the cleaner body and handle are substantially the same as shown in Fig. 1 to which reference may be had for details of construction, the difference being in the form of bag employed. In this modification the bag 25f includes a flexible neck 28f integrally with the cleaner bag and suitably reinforced externally as is the neck of the bag shown in Fig. 9, the purpose being to resist strain. In the present modification however the bag is shown as externally reinforced throughout its extent by means of suitable netting 26f preferably adhesively secured thereto, the bag being supported from the handle 18f by means of a loop 30f which in this case is provided with a clasp which engages the outside of the bag adjacent the neck portion, this arrangement being possible owing to the reinforcement of the bag. The mounting of the bag as herein shown confines the locus of flexibility substantially to the extended neck of the bag. If desired a loop similar to those shown in Figs. 1, 7, 9 or 11 may be used for supporting the bag neck from the handle. A rotatable valve 14f serves to selectively place the suction handle 18f or the floor tool 16f in communication with the fan (not shown) according to the position of the valve.

While various types of reinforced paper bags have been described and also various types of cleaners it will be understood that these forms are illustrative only and that the various modifications of the bag may be employed with different forms of cleaners as have been suggested in this specification.

Where a permanent reinforcement of the bag is desired this should be cheap to apply so that the entire bag will be sufficiently inexpensive to be thrown away. Various forms of reinforcements are suggested in Figs. 13, 14, 15 and 16.

In Fig. 13 the body of the bag 25 is composed of porous paper 25 and to both surfaces of this paper a netting 26 may be adhesively applied. The reinforcement may be of cheap material such as mosquito netting. In Fig. 13 the setting is shown applied to one surface only of the paper. In the formed bag it will be obvious that this reinforcement may be either inside or outside, as illustrated in Figs. 1 and 12 for example.

If desired the netting may be rolled into the pulp during the course of manufacture without the use of an additional adhesive. Such a construction is contemplated in the surface shown in Fig. 15. Where the threads are applied after the paper has been manufactured care should be exercised to avoid spreading the adhesive over the surface of the paper thus reducing the porosity of the filter, it being desirable that the ad-

hesive be confined only to the points of contact between the netting and the paper.

In Fig. 16 the reinforcement is shown in the form of irregularly arranged fibers within the paper itself which fibers may be incorporated into the paper during any suitable stage of manufacture.

These methods of reinforcing the paper and also methods of forming the bag are described in greater detail in my application Ser. No. 552,050 10 to which reference may be had for further details.

It will be understood that the various types of reinforced bags herein described may be used with any of the forms of cleaners disclosed herein and also with other cleaners which are adapted to the purpose of the present invention. Numerous variations and modifications within the spirit of my invention will be suggested to those skilled in the art and these are intended to be included within the scope of the appended claims. 20

The present application being a continuation-in-part of my applications Serial Nos. 499,575 and 552,050, the entire disclosures of such applications are hereby incorporated by reference as part of the present description. 25

I claim:—

1. In a suction cleaner, having an exhaust outlet pipe and a hinged handle; a dust collecting and air filtering bag carried by the handle and composed of reinforced porous paper, a strong 30 flexible connecting neck communicating at one end with the mouth of the bag and at the other with the outlet pipe, and means for supporting the mouth of the bag from the handle, whereby the movement of the handle is absorbed by said 35 flexible neck.

2. In a suction cleaner having an exhaust outlet pipe and a hinged handle; a dust collecting and air filtering bag carried by the handle and composed of porous paper having a reinforcing 40 net cover, and a non-porous tube connected at one end with the mouth of the bag and at its opposite end with the exhaust outlet pipe, said tube being of sufficient length and flexibility to minimize the strain upon the mouth of the bag 45 when the handle is flexed.

3. In a suction cleaner having an exhaust outlet pipe and a hinged handle; a dust collecting and air filtering bag carried by the handle and composed of reinforced porous paper, and a non-porous flexible connecting tube interposed between the mouth of the bag and the outlet pipe, and means for so supporting the mouth of the bag from the handle that the movement of said handle is absorbed by said flexible tube without 55 strain on said bag.

4. A suction cleaner having a swiveled handle and an air filtering bag, comprising an inner porous paper receptacle and an outer reinforcing receptacle of relatively coarse mesh fabric 60 with which the inner receptacle contacts when the bag is inflated, said bag being connected to the exhaust of said suction cleaner, and attached at its upper end to said handle, means for supporting the neck of the bag from the handle of 65 the cleaner, and a flexible connector extending between the exhaust of said suction cleaner and the mouth of said bag forming the locus of flexibility between the exhaust of said suction cleaner and said bag.

5. In a suction cleaner, a body having a discharge outlet, a handle hingedly mounted with reference to said body, a porous paper dust collecting and air filtering bag adapted to be carried by the handle and having a reduced neck, 75

5 a flexible tube connecting the discharge outlet with the neck of the bag, and a rigid member supporting the bag end of the flexible tube so as to constrain said tube end to move in unison with the handle and thereby relieve the bag neck of strains.

6. In a suction cleaner, a body having a discharge outlet, a handle hingedly mounted with reference to the said body, a porous paper dust 10 collecting and air filtering bag adapted to be carried by the handle and having a reduced neck, a flexible tube connecting the discharge outlet with the neck of the bag, and means for rigidly supporting the bag neck at a fixed distance from the 15 handle.

7. In a suction cleaner, a body unit having a fan casing outlet, a handle hingedly mounted with reference to the body unit, a porous paper dust collecting and air filtering bag, a flexible 20 tube connected to said fan outlet and communicating with the bag mouth, a rigid connection between the handle and that end of the flexible tube remote from the fan outlet so that on pivoting the handle the end of the tube rigidly attached thereto is constrained to move therewith, and a coupling provided at the end of the tube to effect a connection between the bag and the tube, the upper end of the bag being connected to the handle.

8. In a suction cleaner, a body unit including a fan casing outlet, a flexible tube communicating with said outlet at one end, a handle hingedly mounted with reference to the body unit, means rigidly connecting the other end of said tube to the handle in fixed relation thereto, and enforcing said other end to move in unison with the handle, and a porous paper dust collecting and air filtering bag an upper region of which is suspended from the handle and a lower region of 40 which has an inlet neck communicating with said other end of the tube and detachable therefrom while the latter remains fixed relative to the handle.

9. A suction cleaner having a swiveled handle 45 and a fabric bag adapted to be connected with the exhaust of said suction cleaner and to be supported at its upper end to said handle, in combination with stiffening means longitudinally coextensive with said bag to prevent flexing of said bag during the manipulation of said handle, and a flexible connector extending between the exhaust of said suction cleaner and said bag forming the locus of flexibility between the exhaust of said suction cleaner and the lower end 50 of said bag.

10. A suction cleaner having a swiveled handle, a dust collecting bag comprised of two coacting layers of fabric, one within the other, adapted to be connected with the exhaust of said suction 60 cleaner and attached at its upper end to said handle, in combination with stiffening means longitudinally coextensive with said bag to prevent flexing of said bag during manipulation of said handle, and a flexible connector extending between the exhaust of said suction cleaner and said bag, forming the locus of flexibility between the exhaust of said suction cleaner and the lower end 65 of said bag.

11. A suction cleaner having a swiveled handle 70 and a dust collector comprising a pair of coacting layers of fabric, one within the other, adapted to be connected with the exhaust of said suction cleaner and attached at their upper ends to said handle, in combination with stiffening means longitudinally coextensive with the outer layer

of fabric to prevent flexing of said layers of fabric during manipulation of said handle, and a flexible connector extending between the exhaust of said suction cleaner and the mouth of said dust collector forming the locus of flexibility between the exhaust of said suction cleaner and the lower end of said dust collector.

12. A suction cleaner having a swiveled handle, and a porous fabric bag adapted to be connected with the exhaust outlet of the suction cleaner and attached at its upper end to said handle, in combination with a stiff member carried by the handle and serving to prevent flexing of said bag during manipulation of said handle, a flexible tube connected at one end with said exhaust and supported at the other by said stiff member, and a coupling member communicating at one end with said flexible tube and at the other with the mouth of said bag, said flexible tube forming the locus of flexibility between the exhaust of said suction cleaner and the lower end of said bag.

13. A suction cleaner having a fixed exhaust outlet, an elongated member hinged to said cleaner, a connector unyieldingly supported by said member, a flexible tubular member secured to and communicating with said exhaust outlet at one end, the other end being attached to the said connector, said connector having means for detachably supporting the open mouth of a flexible bag in communication with said flexible tubular member, whereby said member may be swung without flexing or straining the bag.

14. A portable suction cleaner, including a cleaning tool, suction producing means adapted to be operatively connected to the cleaning tool 35 and having an exhaust outlet, a casing for said suction producing means, a handle carried by the cleaner and movable with respect to the suction producing means, a rigid guard frame carried by the handle, a dust collector bag carried by the 40 guard frame, a flexible conduit connecting the mouth of the dust bag and the exhaust outlet, and a bracket carried by the casing of the suction producing means, said guard frame being hinged to said bracket, the axis of the hinge 45 passing through the said flexible conduit.

15. In a portable electrically operated suction cleaner, including a motor driven fan, a fan casing having a suction inlet and exhaust outlet, a cleaning tool operatively connectible to the suction inlet, and a handle carried by the cleaner; the improvement which comprises a rigid hollow guard frame carried by the handle, an electric conduit passing through the guard frame for supplying current to the motor, and a dust collector bag carried within said guard frame.

16. A guard for the dust collector bag of a portable electric suction cleaner, comprising a hollow frame adapted to enclose three sides of the dust collector, and serving as a housing for an electric conduit for supplying the electric motor of the suction cleaner.

17. In a portable suction cleaner having a handle movable with reference to the body of the cleaner and an exhaust outlet for dust laden air; a dust filtering bag composed of porous material which is inexpensive but of insufficient strength to withstand the repeated bendings which would occur if the mouth of the bag were connected directly to the cleaner outlet, a flexible 65 tubular member connecting the mouth of the bag with said outlet, and a rigid bag supporting member beneath and attached to the handle and pivotally connected to the cleaner adjacent said outlet.

18. In a portable suction cleaner, including a cleaning tool, suction producing means adapted to be operatively connected to the cleaning tool and having an exhaust outlet, a handle carried by the cleaner and movable with respect to the suction producing means; a rigid guard frame beneath and attached to the handle, a porous, paper dust collector bag carried by the guard frame, a flexible conduit connecting the mouth of the dust bag and the exhaust outlet, and a bracket carried by the casing of the suction producing means, said guard frame being hinged to said bracket.
19. In a portable suction cleaner, an exhaust outlet pipe for dust laden air, a handle movable with reference to the body of the cleaner; coupling and supporting means for attachment of a dust filtering bag to the cleaner, comprising a ring having a hinged connection with the outlet pipe, a flexible tubular member connecting said ring and outlet pipe, an arm beneath and attached to said handle, rigidly connected to said ring and adapted to support said bag at one end, and means for detachably connecting the other end of the bag thereto.
20. In a device of the character described, a suction cleaner body having a fixed dust outlet, a handle and a bar pivotally connected to said cleaner, a rigid connection between the bar and handle spaced from the cleaner, a porous dust collecting and air filtering bag supported beneath the handle, a coupling ring connecting the bag and bar and spaced from the body of the cleaner, and a flexible conduit connecting and communicating with the cleaner outlet and bag, the end of the conduit connected with the bag supported by the bar.
21. A suction cleaner body having a fixed dust outlet, a handle and an elongated bag-supporting member pivotally connected to said cleaner body, said bag-supporting member being beneath the handle and connected thereto, a connector unyieldingly supported by said member, a flexible tubular member secured to and communicating with said dust outlet at one end, the other end being attached to the said connector, said connector having means for detachably supporting the open mouth of a flexible bag in communication with said flexible tubular member, whereby said handle and bag-supporting member may be swung without flexing or straining the bag.
22. In a portable suction cleaner having a fixed exhaust outlet for dust-laden air and a pivoted handle movable with reference to the exhaust outlet; a porous paper dust filtering bag, a flexible non-porous tubular member connecting the bag mouth with said fixed outlet, a rigid bag supporting member beneath and attached to the handle, and means for detachably securing the bag to said supporting member.
23. In a portable suction cleaner, a body portion having an outlet for dust laden air, a handle movable with reference to the body of the cleaner; a rigid member beneath and attached to the handle and pivotally connected to the body of the cleaner, a porous paper dust collecting bag carried by the rigid member, and a flexible conduit connecting the mouth of the bag and said outlet.
24. A suction cleaner as set forth in claim 23, wherein the handle and rigid member swing about the same pivot.
25. A suction cleaner as set forth in claim 23, wherein the handle and rigid member swing about an axis passing through the flexible tube.
26. In a portable suction cleaner, a body including a source of suction, a suction nozzle adapted to be placed in communication with said source of suction, an outlet for dust laden with air, a handle movable with reference to the cleaner body, a rigid member beneath and attached to the handle and pivotally connected to the body of the cleaner, a porous paper dust collecting bag attached to said rigid member, and a flexible tubular member connecting the mouth of the bag with said outlet.
27. A portable suction cleaner as defined in claim 26, wherein the handle is hollow and is adapted to be placed in communication with the source of suction through a flexible conduit, and valve means are provided for selectively connecting the nozzle and said handle to the source of suction.
28. In a portable suction cleaner, a body portion including an exhaust outlet for dust laden air, a handle movable with reference to the body of the cleaner; a pair of spaced lugs extending rearwardly from the body portion adjacent said outlet, a rigid member beneath and attached to the handle having means pivotally connected to said lugs, a porous paper air filtering bag carried by said rigid member, a connector ring carried by said rigid member and fitting the mouth of the bag and a flexible hollow conduit for establishing communication between the connector ring and said exhaust outlet.
29. In a portable suction cleaner, a body portion including a fan having an inlet and a discharge outlet, a pair of suction passages adapted to be connected to said inlet, valve means for controlling said passages, a suction nozzle connected to one of said passages, a suction handle movable with reference to the body of the cleaner and connected to the other of said suction passages by means of a flexible tube, a rigid member beneath and attached to said handle and pivotally connected to the body of the cleaner, a porous air filtering bag carried by said rigid member, a connector ring carried by said rigid member and fitting within the mouth of the bag, and a flexible conduit connecting said ring with the fan discharge outlet.

DANIEL BENSON REPLOGLE.
